UNITED STATES PATENT OFFICE.

GEORGE EDWARD KRIDER, OF HOLLIDAYSBURG, PENNSYLVANIA, ASSIGNOR TO
MCLANAHAN-STONE MACHINE COMPANY, OF HOLLIDAYSBURG, PENNSYLVANIA,
A CORPORATION OF PENNSYLVANIA.

REMOVABLE SEGMENT FOR CRUSHER ROLLS.

Application filed October 5, 1927. Serial No. 224,222.

This invention relates to an improvement in crushers of the single roll type and has primarily in view novel means for securing the crushing segments to the rolls in such a 5 manner as to facilitate replacement.

Another object of the invention is to provide means for yieldably maintaining the segment securing means in tight engagement upon the roll at all times, thereby preventing 10 any lost motion between the segments and the roll spider.

A further object is to provide means for constructing and assembling the elements of a crusher roll in a simple and practical manner, which is strong and durable, efficient and reliable in performance, relatively inexpensive to manufacture, and otherwise well adapted for the purposes for which the same 15 is intended.

20 Other objects and advantages reside in the special construction and combination of the various elements comprising the invention, reference being had to the accompanying drawings, wherein:—

25 Figure 1 is an end elevational view of an assembled crusher roll constructed in accordance with my invention.

Figure 2 is an elevational view looking toward the face of the roller, with parts shown 30 in section, as taken substantially along a line 2—2 of Figure 1.

Figure 3 is a perspective view of one of the retaining wedges, and,

35 Figure 4 is a fragmentary transverse sectional view of a portion of the spider showing the relative position of one of the segments carried thereby.

One of the novel and distinctive features of the present invention is the provision of a 40 crusher roll consisting of a plurality of segmental shoes which are effectively locked in position on a spider or bed roll in such a manner that they may be readily assembled to provide the crushing surface, and at the same 45 time, may be easily removed when desired for replacement or repairs.

Referring particularly to the details illustrated by the drawings, a pair of spider hubs are indicated at 5 disposed in spaced parallel 50 relation upon a shaft 6 and having their outer periphery formed of a plurality of segment holding ribs 7. The ribs are arranged in spaced parallel relation and comprise alternately arranged smaller ribs 8 and relatively

larger ribs 9, the latter preferably being of 55 a substantially dove-tailed formation as clearly shown in Figure 4 of the drawing.

The spider thus formed from the hub and ribs is adapted to carry crusher segments 10 extending longitudinally of the shaft, each 60 end of the segment having aprons 11 overlapping the outer end of the segments of the spider. The inner faces of each of the segments 10 are provided with legs 12 and 13 adapted to be seated within the recesses 65 formed between the ribs 8 and 9, one of the legs indicated at 13 being considerably smaller than the recess within which the same is seated whereby to enable a wedge 14 to be inserted in the recess together with the legs 70 whereby through the frictional engagement of the wedge with the dove-tailed edge of the rib 9 to retain the segments in position on the spider.

The wedge 14 has one or more of its faces 75 tapered to provide a tapering engagement between the rib 9 and leg 13 and is also formed with a longitudinally extending bore 15, each end of each segment being provided with one of the wedges as illustrated in Figure 2 so as to securely retain each end of the segment in position on the spider. A spiral spring 16 extends between the wedges 14 at the opposite ends of each segment, the spring being inserted through the bore 15 thereof 80 with the outer end of the spring tensionally secured against removal from the wedge by keys 17 inserted through one of the convolutions of the end of the wedge, the tension of the spring serving to prevent the slipping of the key 17 from the end thereof. A counter-sink 85 18 is formed in the outer end of each of the wedges within which the key 17 may seat so as to prevent the slipping of the keys from 90 the spring. A counter-sink 18 is formed in the outer end of each of the wedges within which the key 17 may seat so as to prevent the slipping of the keys from 95 the spring.

One end of each of the segments 10 is provided with a projection or overhang indicated at 19 in Figure 4 adapted to seat upon the outer end of the adjacent smaller rib 8, 100 thereby forming a solid supporting means for that end of the segment and preventing any tendency of the segment to turn on the spider.

If desired the inner face of the segments 105 at their point of contact with the ribs may be provided with a covering 20 of type metal or similar material to form a true and close

fitting joint between the segment and ribs at such points of contact.

The outer surface of each of the segments is formed with crusher teeth 21 of the usual 5 construction.

It will be apparent that should any of the teeth of the segments become worn or broken, the entire segment may be readily replaced by removing the keys 17 which enables the 10 spring 16 and wedges 14 to release the segments after which the same may be readily removed from the spider and repaired or replaced by a new segment.

It is obvious that the invention is susceptible of various changes and modifications without departing from the spirit or scope of the appended claims or sacrificing any of its advantages, and I accordingly claim all 15 such forms of the device to which I am entitled.

I claim:—

1. A crusher roll construction including a 20 crusher spider having a plurality of segment holding ribs, crusher segments removably supported by said ribs, a wedge at each 25 end of said segment frictionally engaging each segment with one of said ribs and a connector for said wedges possessing a relatively high degree of elasticity throughout 30 its length.

2. A crusher roll construction including a 35 crusher spider having a plurality of holding ribs formed thereon, a plurality of crusher segments carried by the ribs and extending 40 at opposite ends of the spider, a pair of wedges frictionally engaging the spider and each segment at opposite ends thereof and a connector for each pair of wedges possessing a relatively high degree of elasticity through- 45 out its length and urging the same into engaged position inwardly of the segment.

3. In an attaching device for crusher roll

segments comprising a pair of tapering wedges engaging the opposite edges of the 45 segment and having a bore extending therethrough, a connector for said wedges possessing a relatively high degree of elasticity throughout its length, a counter sink at the 50 end of the bore and each wedge adjacent the larger end thereof, and a pin attachable at each end of the connector and seated within said counter sink whereby to prevent lateral movement of the pin.

4. A crusher roll construction including a 55 crusher spider having a plurality of pressure segment holding ribs arranged in spaced parallel relation, each alternate rib being of a substantially dove tailed formation, a plurality of crusher segments carried by the spider, each of said segments having aprons 60 formed at each end thereof in overlapping relation with the ends of the spider, legs formed on the inner face of the segment adapted to seat between the rib of the spider, a wedge arranged at each end of each of the 65 segments and adapted for insertion in frictional engagement between one of the legs of the segment and an adjacent dove tailed rib, a connector extending between the oppositely disposed wedges possessing a relatively high 70 degree of elasticity throughout its length for retaining the wedges against outward movement, a key carried at each end of the connector retaining the same in engaged position with the adjacent wedge and a projection 75 formed on the under side of each of the segments having one side engageable with one of said ribs and its opposite side engageable by one of the wedges and frictionally retained therebetween by the action of said so wedge.

In testimony whereof I affix my signature.

GEORGE EDWARD KRIDER.
